UNITED STATES PATENT OFFICE.

EMIL CORNELY, OF PARIS, FRANCE.

EMBROIDERING-MACHINE.

SPECIFICATION forming part of Letters Patent No. 292,285, dated January 22, 1884.

Application filed June 30, 1883. (No model.) Patented in France May 23, 1882, No. 149,127, and in England May 25, 1882.

To all whom it may concern:

Be it known that I, EMIL CORNELY, of Washington city, in the District of Columbia, a resident of the city of Paris, in the Republic 5 of France, have invented a new and useful Improvement in Embroidering-Machines, which is fully set forth in the following specification.

The present invention relates to certain improvements in embroidery-machines, for 10 which Letters Patent were obtained August 15, 1882, No. 262,743.

As the invention relates only to certain details in the construction of said machine, they 15 will be best understood by reference to the following description and the annexed drawings, in which—

Figures 1 and 2 represent views which are analogous to those represented in Figs. 4 and 5 of Patent No. 262,743. Figs. 3 and 4 are 20 detail views, and Fig. 5 a partial view in section through wheel I.

In the above-named patent the operation of the sleeve S was not found sufficiently reliable when the machine was to run at a high speed, 25 and did not afford sufficient facilities for regulating the height of said sleeve when it was found necessary to adjust the distance of the blades G from the needles.

As the general construction and operation 30 of the machine is not modified, the present description is confined only to the modifications made.

The sleeve S is actuated in its rising and descending motion by the lever G, which is 35 pivoted at i to the frame Z. A stud, 12, is journaled within the lever G, Fig. 2, and a friction-roller, 13, which turns on stud 12, extends into a cam-groove, 14, of the sliding block 15, which can slide freely upon the 40 fixed bar 16. The sliding block 15 receives its horizontal reciprocating motion from the rod N and collar T, into which extends the part 17 of the rod v, which slides within the frame H' and through the collar 18 of rod v, 45 into which extends a tooth of the sliding block 15. The friction-roller 13 is adjusted eccentrically upon the stud 12, (see Fig. 3,) so that by turning the head 19 of said stud the lever G, the sleeve S, and consequently the lever V,

will be raised or lowered, and the blades, 50 (lettered G in the patent,) which are secured to the vertical arm of said lever, will respectively be brought nearer to or farther away from the needles, thus affording the means of supplying more or less thread to 55 said needles, as may be necessary, according to the length of the stitches or the material to be worked. When the head 19 of stud 12 has been turned to the position required, it is fixed by the action of spring-pawl 20, which 60 drops into one of the spaces between the teeth, which are cut out, on the circumference of the head 19. (See Figs. 3 and 4.) By the horizontal reciprocating motion of rod N the collar T acts upon part 17 of sliding 65 rod v, and drives the latter, as well as the collar 18 and sliding block 15, all in a horizontal direction. The action of the incline of the cam-groove 14 upon the friction-roller 13, and consequently upon its lever G, imparts to 70 the latter a vertical reciprocating motion, which is transmitted to the sleeve S, to the lever V, and thence to the blades which supply the thread to the needles.

The letters not referred to herein represent 75 the parts indicated by the same letters in the patent.

Having thus fully described the nature of my invention, what I claim is—

1. In an embroidery-machine, the combination, with the sleeve for operating the blades that supply thread to the needles, of the lever connected with said sleeve and reciprocating the same, the sliding block having a cam-groove, the stud on said lever entering 85 said groove, and mechanism, as specified, for reciprocating said sliding block, substantially as described.

2. In an embroidery-machine, the combination of the blades, the sleeve connected therewith, as set forth, the lever for operating said sleeve, the sliding block having a cam-groove, the stud on said lever entering said groove, and the rod v, having a groove which receives a tooth of said block, and provided 90 with a projection which engages collars on the horizontal rod N, substantially as described.

3. The combination of the lever and con-

nections, as specified, for communicating motion to the blades, the sliding block having a cam-groove, and the eccentric pin or roller carried by said lever and entering said groove, with means for operating said pin, whereby the stroke of said blades, and consequently the amount of thread supplied, may be regulated, substantially as described.

In testimony whereof I have signed this specification in the presence of two subscribing witnesses.

EMIL CORNELY.
